UNITED STATES PATENT OFFICE.

MILTON H. BALCH AND FELIX LANGE, OF CHICAGO, ILLINOIS; SAID LANGE ASSIGNEE
TO SAID BALCH.

HOLDER FOR PAPER BAGS AND THE LIKE.

1,131,310.

Specification of Letters Patent.

Patented Mar. 9, 1915.

Application filed November 4, 1912. Serial No. 729,411.

To all whom it may concern:

Be it known that we, MILTON H. BALCH and FELIX LANGE, citizens of the United States, residing at Chicago, Cook county, Illinois, have invented certain new and useful Improvements in Holders for Paper Bags and the Like, of which the following is a specification.

Our invention relates to holders for paper bags and other similar articles which are supplied in a bunch and required to be used one at a time and the object thereof is to provide a holder of this character which shall be comparatively simple of construction and economical of manufacture as well as efficient and reliable in use.

The various features of novelty and utility in our holder will be apparent from the description hereinafter given.

20 In the drawing Figure 1 is a perspective view of our holder showing the same in connection with a bunch of paper bags representing one of the uses of our invention, and Fig. 2 a similar section of the device but 25 with the bunch or supply of bags omitted and showing the roller in its innermost position.

Referring to the present embodiment of our invention as illustrated in the drawing 30 the holder comprises a shell 1 of suitable size and dimensions according to the size and width of the articles such as paper bags which will be hereinafter referred to as the article held although our invention is not limited to a mere bag holder. This shell 35 may be made of any suitable material preferably sheet metal and the same is substantially U-shape in cross section. In order to provide a support for this shell and a place 40 of attachment for the springs, a frame is employed, the same comprising two opposite side members or strips 2 having flanges 2^a at their lower ends which are secured to the shell and connected at their upper ends 45 by a cross bar 3. This cross bar may be provided with any suitable means for supporting the entire holder and in the present instance an eye 4 is shown adapted for this purpose.

Within the shell 1 and within the plane 0 of its longitudinal axis is a bar 5 of suitable material and preferably rotatably mounted. In the present instance this roller is mounted to rotate and is also held upwardly 5 pressed with yielding pressure toward the innermost portion of the shell by means of a pair of independent springs 6, 6. These springs are of the coiled type and are operatively connected at their lower ends with the screws 7, projecting laterally from the 60 opposite ends of the roller, the connection being such that the roller is free to move or partially rotate whenever the innermost bag of the supply shown at A is withdrawn. The upper ends of these springs are secured 65 to the frame through the medium of the eyes 8.

In order to provide a handle or means of enabling the operator to withdraw the roller sufficiently to permit a supply of bags to be 70 inserted within the holder or shell we employ a flexible device secured to the screws 7 at the opposite ends of the roller, which device may be a cord, chain or the like but which is here shown as a chain 9 normally 75 hanging below the roller and in position to be readily grasped by the operator for the purpose above explained.

In practice the entire holder is suitably suspended or supported by a support in a 80 fixed movable relationship therewith but held suspended against downward movement in order that the bags may be withdrawn in the manner to be described. In filling the holder, the operator grasps the 85 chain 9 and pulls the roller 5 downwardly against the tension of the springs 6 which act independently at opposite ends of this roller. The chain is grasped by one hand of the operator who with his other hand then 90 inserts the open ends of a bunch of paper bags, such bags being inserted as shown in Fig. 1 between the roller and the shell or holder proper, the ends of the bags being preferably combed. The operator thereupon 95 releases his grip upon the chain with the result that the roller 5 will bear against the turned-over upper ends of the bags and hold them with a yielding pressure against the innermost portion of the shell. By reason 100 of the employment of the independent springs the roller 5 adapts itself well to the bunch of bags and hold the same in proper relationship with the shell. When it is desired to use a bag the innermost one, that is 105 the first one shown in Fig. 1 is grasped at its lower end and by a quick movement or jerk such bag is withdrawn without disturbing any other bags of the bunch. The construction is such that the bags are properly and 110

2
firmly held in position for use regardless of the size of the bunch.

To accommodate the different sizes of bags used by consumers, a plurality of these holders are employed of a size according to the size of the bags. These holders may be supported in any suitable manner at the place or places of use and in convenient reach of the user, for instance they may be strung upon 10 a common rack or like support.

We claim:

1. In a device of the class described, the combination of a frame, a member depending therefrom to form a receptacle for one 15 end of a bunch of bags, etc., a bar capable of movement in the arc of a circle, and springs connected with the ends of the bar and forming the sole support thereof, said springs normally holding the bar toward 20 said receptacle.

2. In a device of the class described, the combination of an inverted U-shaped receptacle to receive one end of a bunch of bags, etc., a frame secured thereto along its central 25 longitudinal axis, a roller capable of a swinging and rocking movement and located within said receptacle, and a pair of springs which are pivoted at one of their ends to the frame and at the other of their ends directly to the ends of said roller, the springs forming the sole support for the roller.

3. In a device of the class described, the combination of a shell which is substantially U-shape in cross section, a frame secured to 35 the shell along its central longitudinal axis, a roller located within the shell, and a pair of independent springs rotatably supporting the opposite ends of the roller and secured to the frame to normally hold such roller to 40 the innermost portion of the shell; substantially as described.

4. In a device of the class described, the combination of a shell which is substantially U-shaped in cross section, a bar positioned 45 within the shell, a frame on said shell, and independent springs connected at one of their ends with the ends of the bar and form-

ing the sole support therefor, the other ends of the spring being pivotally connected with 50 said frame.

5. In a device of the class described, the combination of a shell which is substantially U-shaped in cross section, a bar positioned within the shell, independent springs connected with the ends of the bar and forming 55 the sole support therefor, and a handle depending from the bar and connected with the opposite ends thereof.

6. In a device of the class described, the combination of a shell which is substantially U-shaped in cross section, a roller positioned 60 within the shell and having screws 7 at its ends, and independent springs 6 connected to said screws and forming the sole support for the roller.

7. In a device of the class described, the combination of a shell which is substantially U-shape in cross section, a frame therefor comprising side pieces 2 secured at one end thereto and a cross piece 3 connecting the 70 other ends of the side pieces, a roller positioned within the shell, and springs 6 secured at their upper ends to the frame and operatively connected at their lower ends to the roller to rotatably support the same 75 and also to hold it within the shell with a yielding pressure.

8. In a device of the class described, the combination, of a frame comprising opposite side pieces 2, 2, having bottom flanges 80 2^a, a top cross piece 3, a shell 1 which is U-shape in cross section and attached to said flanges to depend therefrom, said shell being open ended, a roller 5 within the shell, and having a substantially universal movement, 85 screws 7 at the ends of the roller, and springs 6 arranged adjacent to said side pieces and connected thereto and to said screws; substantially as described.

MILTON H. BALCH.
FELIX LANGE.
